Application September 17, 1937, Serial No. 164,338

27 Claims. (Cl. 164—93)

The present invention relates to ornamenting machines, and work supports thereof, which are used in the manufacture of shoes to provide fitted shoe uppers with ornamental cut-outs or 5 perforations. By a fitted shoe upper we mean one that is finished, at least to the extent of being lined, but which may or may not be closed at the heel.

In ornamenting fitted shoe uppers, it is often 10 desirable to provide the opposite side faces thereof with cut-outs or groups of perforations, the cut-out or group of cut-outs or perforations on one side face being the opposite duplicate laterally, but not longitudinally, of the cut-out or 15 group of cut-outs or perforations upon the other side face. Heretofore, these opposite duplicates have been formed by the same die, acting in one cycle of operations of the ornamenting machine to form the ornamentations on one side face of 20 the fitted shoe upper and acting in another cycle of operations of the machine to form the ornamentations on the other side of the fitted shoe upper.

In order to form the opposite duplicate ornaments by the same die, it was necessary to 25 cut into one side face of the fitted shoe upper from the grain or finished face thereof in one operation, and to cut into the other side face of the fitted shoe upper from the lined face thereof.

To accomplish this, it was necessary for the 30 operative of the ornamenting machine to place the fitted shoe upper upon the work support, locate the fitted shoe upper on the work support by means of a combined clamp and gage registerable 35 with some part of the grain or finished face of the fitted shoe upper, push the work support carrying the clamped upper into the position of pressure, trip the clutch to cause the die to ornament one side face of the fitted shoe upper, without 40 draw the work support from the position of pressure into the position of clearance, unclamp the fitted shoe upper, remove the fitted shoe upper, turn it inside out, place the fitted shoe upper, turned inside out, upon the work support, 45 regage and reclamp the turned inside out fitted shoe upper, the gage and clamp acting upon the lined side of the remaining uncut side face of the fitted shoe upper, return the work support carrying the gaged and clamped upper to the

50 position of pressure, retrip the clutch to cause the die to cut the other side face of the fitted shoe upper from the lined face thereof, and return the work support to the position of clearance. Experience has demonstrated that it is 55 practically impossible to relocate the turned in-

side out fitted shoe upper on the work support for the second ornamenting operation exactly as the fitted shoe upper was located on the work support for the first ornamenting operation. In consequence, the ornamentations were inaccurately placed on the side face of the fitted shoe upper during the second ornamenting operation, resulting in a lack of correlation between the ornamentations on the opposite side faces 5 of the finished shoe.

Moreover, there is a distinct difference in appearance between the ornamentations in the grain or finished side faces of the finished shoe, those ornamentations made by cutting through 10 from the grain or finished face having attractive 15 burnished edges, while those made by cutting through from the lined face have unattractive burred edges.

In some ornamenting machines the dies are 20 located above the work, while in other ornamenting machines the dies are located below the work, but it is clear that in both types of machines as 25 operated heretofore, the formation of opposite duplicates laterally, but not longitudinally, in the 30 opposite side faces of the fitted shoe upper necessitated the inversion of the fitted shoe upper at some stage of the operation either subsequently to the first ornamenting operation and prior to the second ornamenting operation, or vice versa.

The principal object of the present invention 35 is to produce an ornamenting machine by which the opposite side faces of the fitted shoe upper may be ornamented in a single machine cycle, preferably simultaneously.

To the accomplishment of this object, a feature of the present invention contemplates the provision in an ornamenting machine having ornamenting means and means for supporting a folded fitted shoe upper, of means for moving 40 the ornamenting means and the work supporting means relatively to cause the ornamenting means to ornament the opposite side faces of the folded fitted shoe upper in a single machine cycle, preferably simultaneously.

In the broader aspects of the present invention, it is immaterial into which face of the folded fitted shoe upper the ornamenting means first penetrate, so long as the opposite side faces of the folded fitted shoe upper are penetrated 50 in a single machine cycle or simultaneously. In order, however, to prevent contrast in appearance between the edges of the ornamenting means on the opposite side faces of the finished shoe it is preferred to cause the ornamenting means to 55

penetrate the opposite side faces of the folded fitted shoe upper from the same face thereof. Preferably, the face of the shoe upper into which the ornamenting means first penetrates is the 5 grain or finished face, in order that the edges of the ornamentations formed in the opposite side faces of the finished shoe may both have the same attractive burnished appearance.

Heretofore, in many shoe upper ornamenting 10 operations, it was desirable to support the fitted shoe upper on an elevated work support, called an anvil, constructed to permit the portion of the shoe upper to be ornamented to be supported flatwise, the side faces of the anvil being constructed to permit the other portions of the fitted 15 shoe upper to be tucked out of the way, so as not to be caught between the ornamenting means and the pressing member. Usually, the anvil carried the dies, so that the portion of the upper 20 to be ornamented was supported flatwise upon the stripper plate thus necessitating the use of a clamp provided with a window, the internal edges of which acted as a gage in locating the upper properly relatively to the ornamenting 25 means. Experience has demonstrated that it is undesirable to employ a work support which requires the use of a clamp or gage which masks or conceals the portion of the upper immediately surrounding the area to be ornamented. Moreover, 30 with an anvil, it is difficult and often impracticable to support flatwise the portion to be ornamented, either of a "Gypsy" vamp having a "California" welt running along its median line or a fitted shoe upper having considerable swing.

35 A further object of the present invention is to produce a work support for supporting fitted shoe uppers for the ornamenting operation which will support flatwise the portion of the upper to be ornamented, and which will permit its clamping and gaging without masking or concealing the portion of the upper immediately surrounding the area to be ornamented.

To the accomplishment of these objects, and such others as may appear hereinafter, the various 45 features of the present invention consist in certain devices, combinations and arrangements of parts hereinafter described and then pointed out broadly and in detail in the appended claims which possess advantages readily apparent to 50 those skilled in the art.

The various features of the present invention will be understood readily from an inspection of the accompanying drawings illustrating the best 55 form of the invention at present known to the inventors, in which,

Figure 1 is a detail view in perspective showing how the right and left dies are mounted in a "Western" cut-out machine so as to cut the opposite sides of a shoe upper simultaneously;

60 Fig. 2 is a similar view showing how the lower die and the work supporting and gaging structure may be moved into a position of clearance to permit the removal of finished work from the work supporting plate, and the substitution 65 thereon of another piece of work for the duplex ornamenting operation;

Fig. 3 is an enlarged detail view in plan of the work supporting and gaging structure;

70 Fig. 4 is a detail view, in right side elevation; Fig. 5 is a detail view in sectional elevation on the line 5—5, Fig. 3, the work being removed from the work supporting plate for convenience;

75 Fig. 6 is a detail view in plan of the lower die guide rails;

Fig. 7 is a detail view in plan of the lower die, and

Fig. 8 is a detail view in bottom plan of the upper die.

For convenience in disclosure, the various features of the present invention are illustrated and described as being embodied in the "Western" 5 cut-out machine of the type disclosed in the patents to Altvater, Nos. 1,834,919 and 1,938,678 granted, respectively, December 8, 1931 and December 12, 1933.

In the embodiment of the invention, illustrated in the drawings, the frame of the machine is shown as including a base 8, (Fig. 4), which is rigidly secured to a permanent horizontal support 9 mounted on legs, (not shown). Integrally formed with the base is an irregularly formed boss 10 constituting a work supporting bed. An overhanging arm is integrally cast with the base 8 and includes the standard 11 and the 15 overhanging head 12. In the upper parts of the standard and head is an elongated journal for the drive shaft 13. This drive shaft is operated intermittently from a suitable source of power 20 acting through a clutch, (not shown), the construction and mode of operation of which is described in the Altvater Patent No. 1,834,919, at page 2, lines 32 et seq.

The shaft 13 carries at its front end an eccentric 14 which rotates within a strap 15 having 30 a downwardly extending arm 16. The arm 16 extends between a pair of spaced arms 17, forming upward extensions of a sliding plunger 18. A pin 19 provides a pivot connection between the arm 16 and the arms 17. The plunger 18 is 35 mounted in a guideway formed on the front face of the head 12. A plate 20 having a rectangular cut-out portion is attached to the walls of the guideway by bolts 21. A die carrier in the form of a sliding block 22 is mounted in the lower part 40 of the guideway in axial alinement with the plunger 18. The connection between the plunger and the die carrier is generally the same in construction and mode of operation as the connection shown in the Altvater Patent No. 1,938,678, 45 so it is unnecessary to repeat that description.

The bottom face of the die carrier 22 is flat to receive flatwise one face of a plate 23 having depending posts 24 upon the lower ends of which the upper or right die 25 is carried. The connection 50 between the die carrier 22 and the plate 23 is substantially the same as between the corresponding parts disclosed in the Altvater Patent No. 1,938,678. The upper or right die 25, as shown in Fig. 8, is provided with perforating tubes 26, arranged 55 in an ornamental design 27.

The lower or left die 28, as shown in Fig. 7, is provided with perforating tubes 29, arranged in an ornamental design 30, which design is the opposite duplicate laterally, but not longitudinally, 60 of the ornamental design 27. The die 28 is mounted flatwise, with the cutting edges of the perforating tubes 29 directly upwardly, upon the flat upper surface 31 of the work supporting bed 10. The die 28 is guided for movement from a 65 position of clearance to and from a position of pressure between spaced rails 32 and 33, (Fig. 6), which are connected at their front and rear ends by cross-pieces 34 and 35, respectively. The cross-piece 35 is provided with a forwardly directed 70 tongue 36, provided with two vertical holes 37 which are received by pins 38 projecting vertically from the surface 31.

The lower die 28 is provided with a rear extension 39 having a fork 40 formed therein which, 75

- when the die 28 is located in the position of pressure, embraces the tongue 36. The tongue 36 thus acts as a stop in limiting the rearward movement of the die 28. The tongue 36 acts also as a gage 5 to locate the homologous cutting edges of the perforating tubes 26 and 29 in the same vertical plane, respectively. The cross-rail 34 acts as a stop to limit the forward movement of the die 28 into the position of clearance.
- 10 The extension 39 on the die 28 is provided with laterally perforated legs 41 and 42 which support a cross-pin 43, the opposite free ends of which rest upon the upper surfaces of the rails 32 and 33, respectively. The pin 43 supports pivotally the 15 depending arms of a yoke 44 to the flat upper surface of which the rear end of a plate 45 is secured. This plate 45 constitutes the work support. As it is positioned between the downwardly directed tubes 26 of the upper die and the upwardly 20 directed tubes 29 of the lower die, the opposite sides of the plate 45 act as striking surfaces cooperating with the tubes of the dies, respectively.
- The work supporting plate 45 is provided with a blind slot 46, shaped to receive the forward portion 25 of a folded fitted upper 47. The fitted upper 47 is folded about the median line of its front portion. The fitted upper thus folded is inserted in the blind slot 46 when the die 28 is located in the position of clearance, (Fig. 2), and at a time when 30 the plate 45 is swung rearwardly about the pin 43 as an axis. The folded fitted upper 47 is hung on the rear edge 48, which is shaped concavely to fit the inside median line of the folded fitted upper.
- As shown in Fig. 5, the other edge 49 of the 35 blind slot is bent downwardly and to the right, viewing Fig. 3, to bring it below the plane of the edge 48.
- A combined clamp and gage 50 is pivoted by one end to the left side, viewing Fig. 3, of the front 40 end of the plate 45, the gage swinging into and out of position in the same horizontal plane as the edge 48. At its free end, the gage 50 is provided with an operating button 51.
- The extension 39 on the die 28 is provided with 45 laterally perforated legs 41 and 42 which support a cross-pin 43, the opposite free ends of which rest upon the upper surfaces of the rails 32 and 33, respectively. The pin 43 supports pivotally the depending arms of a yoke 44 to the flat upper 50 surface of which the rear end of a plate 45 is secured. This plate 45 constitutes the work support. As it is positioned between the downwardly directed tubes 26 of the upper die and the upwardly directed tubes 29 of the lower die, the opposite 55 sides of the plate 45 act as striking surfaces cooperating with the tubes of the dies, respectively.
- The work supporting plate 45 is provided with a blind slot 46, shaped to receive the forward portion 60 of a folded fitted upper 47. The fitted upper 47 is folded about the median line of its front portion. The fitted upper thus folded is inserted in the blind slot 46 when the die 28 is located in the position of clearance, (Fig. 2), and at a time when 65 the plate 45 is swung rearwardly about the pin 43 as an axis. The folded fitted upper 47 is hung on the rear edge 48, which is shaped concavely to fit the inside median line of the folded fitted upper.
- As shown in Fig. 5, the other edge 49 of the 70 blind slot is bent downwardly and to the right, viewing Fig. 3, to bring it below the plane of the edge 48.
- A combined clamp and gage 50 is pivoted by one end to the left side, viewing Fig. 3, of the front 75

end of the plate 45, the gage swinging into and out of position in the same horizontal plane as the edge 48. At its free end, the gage 50 is provided with an operating button 51.

The rear end of the combined clamp and gage 50 is provided with an edge 52, the rear end of which is shaped convexly to engage the external median line of the folded fitted upper, and clamp it against the concaved edge 48. The rear end of the edge 52 is shaped also to register with some 10 part of the folded fitted upper and thus act as a gage to locate the work on the plate properly for its ornamentation by the dies.

For purposes of disclosure the folded fitted upper is illustrated as a "Gypsy" vamp having a 15 "California" welt along its median line and provided with cross-straps 53 connecting the portion of the opposite side faces to be ornamented. The rear end of the edge 52 is provided with a notch 54, which embraces one of the straps 53, and thus 20 25 gages the work for the ornamenting operation.

For purposes of disclosure the various features of the present invention have been illustrated and described in an extremely simple form. The 25 ornamentations may be perforations, cut-outs, chisel cuts, impression marks, inked marks or any desirable combination thereof. The dies may or may not be associated with stripper plates.

While the particulars of construction herein set forth are well suited to a simple structural 30 form of the invention, it is not limited to these details of construction, nor to the conjoint use of all their features, nor is it to be understood that these particulars are essential, since they may be modified within the skill of the artisan without 35 departing from the true scope of the actual invention, characterizing features of which are set forth in the following claims by the intentional use of generic terms and expressions, inclusive of various modifications.

40

What is claimed as new, is:

1. An ornamenting machine having, in combination, ornamenting means, means for supporting a folded fitted shoe upper, and means for moving the ornamenting means and the work supporting means relatively to cause the ornamenting means to ornament the opposite side faces of the folded fitted shoe upper in a single machine cycle.

45

2. An ornamenting machine having, in combination, ornamenting means, means for supporting a folded fitted shoe upper, and means for moving the ornamenting means and the work supporting means relatively to cause the ornamenting means to ornament the opposite side faces of the folded fitted shoe upper simultaneously.

50

3. An ornamenting machine having, in combination, ornamenting means, means for supporting a folded fitted shoe upper, and means for moving the ornamenting means and the work supporting means relatively to cause the ornamenting means to cut the opposite side faces of the folded fitted shoe upper from the same face thereof.

55

4. An ornamenting machine having, in combination, ornamenting means, means for supporting a folded fitted shoe upper, and means for moving the ornamenting means and the work supporting means relatively to cause the ornamenting means to cut the opposite side faces of the folded fitted shoe upper from the grain or finished face thereof.

60

5. A duplex ornamenting machine having, in combination, a die for ornamenting one side of a fitted shoe upper, a separate die for ornament-

75

- ing the opposite side of the fitted shoe upper, and means interposed between the opposite sides, of the fitted upper, for supporting them in position to be ornamented by the dies, respectively.
5. 6. A duplex ornamenting machine having, in combination, a die for ornamenting one side of a fitted shoe upper, a separate die for ornamenting the opposite side of the fitted shoe upper, and means interposed between the dies for supporting 10 the opposite sides of the fitted upper in position to be ornamented by the dies, respectively.
7. A duplex ornamenting machine having, in combination, a die for ornamenting one side of a fitted shoe upper, a separate die for ornamenting 15 the opposite side of the fitted shoe upper, and means interposed between the dies and the opposite sides of the fitted upper for supporting them in position to be ornamented by the dies, respectively.
- 20 8. A duplex ornamenting machine having, in combination, a die for ornamenting one side of a fitted shoe upper, a separate die for ornamenting the opposite side of the fitted shoe upper, each die having at least one of its cutting edges directed 25 towards the other, and means for supporting the opposite sides of the fitted upper in position to be ornamented by the dies, respectively.
9. A duplex ornamenting machine having, in combination, a die for ornamenting one side of a 30 fitted shoe upper, a separate die for ornamenting the opposite side of the fitted shoe upper, each die having at least one of its cutting edges directed towards the other, and a plate having die striking surfaces upon its opposite faces interposed between 35 the dies and positioned within the upper.
10. A duplex ornamenting machine having, in combination, a die for ornamenting one side of a fitted shoe upper, a separate die for ornamenting the opposite side of the fitted shoe upper, each 40 die having at least one of its cutting edges directed towards the other, and means for supporting flatwise that portion of both sides of the fitted upper to be ornamented.
11. A duplex ornamenting machine having, in combination, a right die for ornamenting the right side of a fitted upper, a left die for ornamenting 45 the left side of the fitted upper, and means for supporting flatwise those portions of the right and left sides of the fitted upper in position to be ornamented simultaneously by the right and left dies, respectively.
12. A duplex ornamenting machine having, in combination, an upper die, for ornamenting one side of a fitted shoe upper, a lower die, for ornamenting 50 the opposite side of the fitted upper, movable from and to a position of clearance to and from a position of pressure, and a work support interposable between the dies and movable with the lower die.
- 60 13. A duplex ornamenting machine having, in combination, an upper die, for ornamenting one side of a fitted shoe upper, a lower die, for ornamenting the opposite side of the fitted upper, movable from and to a position of clearance to and from a position of pressure, and a pivotally mounted work support interposable between the dies and movable with the lower die.
14. A duplex ornamenting machine having, in combination, an upper die, for ornamenting one side of a fitted shoe upper, a lower die, for ornamenting 65 the opposite side of the fitted upper, movable from and to a position of clearance to and from a position of pressure, a pivotally mounted work support movable with the lower die, and a gage pivoted to the work support.
15. A duplex ornamenting machine having, in combination, a right die for ornamenting the right side of a fitted shoe upper, a left die for ornamenting the left side of the fitted shoe upper, said dies being movable relatively towards each other to ornament simultaneously the right and left sides of the fitted upper, respectively, said dies being relatively movable in a direction normal to the first named relative movement to move at least one of the dies from and to a position of clearance to and from a position of pressure, and a work support connected to move with one of the dies. 5
16. In a duplex ornamenting machine the combination with right and left dies, of a work support, interposable between the dies, provided with a blind slot adapted to receive at least the front portion of a folded fitted shoe upper. 15
17. In a duplex ornamenting machine the combination with right and left dies, of a work support, interposable between the dies, provided with a blind slot adapted to receive at least the front portion of a folded fitted shoe upper, said slot having an edge adapted to engage at least a portion of the inside median line of the folded fitted shoe upper. 20
18. In a duplex ornamenting machine the combination with right and left dies, of a work support, interposable between the dies, provided with a blind slot having an edge adapted to engage at least a portion of the inside median line of a folded fitted shoe upper, the opposite edge of the slot lying in a different plane than the first named edge. 30
19. In a duplex ornamenting machine the combination with right and left dies, of a work support, interposable between the dies, provided with a blind slot having an edge adapted to engage at least a portion of the inside median line of a folded fitted shoe upper, the opposite edge of the slot lying in a different plane than the first named edge, and a gage mounted on the plate to engage at least a portion of the outside median line of the folded fitted shoe upper and locate the folded fitted shoe upper properly relative to the dies. 35
20. In a duplex ornamenting machine the combination with right and left dies, of a work support, interposable between the dies, provided with a blind slot having an edge adapted to engage at least a portion of the inside median line of a folded fitted shoe upper, the opposite edge of the slot lying in a different plane than the first named edge, and a clamp mounted on the plate to engage at least a portion of the outside median line of the folded fitted shoe upper and clamp the folded fitted upper to the plate. 50
21. In a duplex ornamenting machine the combination with right and left dies, of a work support, interposable between the dies, provided with a blind slot having an edge adapted to engage at least a portion of the inside median line of a folded fitted shoe upper, the opposite edge of the slot lying in a different plane than the first named edge, and a combined gage and clamp mounted on the plate to engage at least a portion of the outside median line of the folded fitted shoe upper, locate the folded fitted shoe upper properly relative to the dies and clamp the located folded fitted upper to the plate. 60
22. In a duplex ornamenting machine the combination with right and left dies, of a work support, interposable between the dies, provided with a blind slot having an edge adapted to engage at least a portion of the inside median line of a 65

folded fitted shoe upper, the opposite edge of the slot lying in a different plane than the first named edge, and a gage mounted on the portion of the plate provided with the last named edge to move in the same plane as the first named edge.

23. In a duplex ornamenting machine, the combination with right and left dies, of a work support, interposable between the dies, and provided with a blind slot shaped to receive the front portion of a folded fitted shoe upper and permit the location of the opposite faces of the folded fitted shoe upper adjacent the slot flatwise upon the opposite faces of the plate, respectively.

10 24. In an ornamenting machine, the combination with an ornamenting die, of a work supporting plate having a blind slot, the plate at one side of the slot acting as a work support for a fitted upper, and a gage mounted on the plate at the other side of the slot.

15 25. In an ornamenting machine, the combination with an ornamenting die, of a work supporting plate having a blind slot, one edge of which is shaped to engage at least a portion of the inside median line of a folded fitted shoe up-

per, the toe portion of which is received within the slot, and a clamp having an edge shaped complementary to the shaped edge of the slot to engage at least a portion of the outside median line of the folded fitted shoe upper and clamp 5 it to the last named shaped edge.

26. In an ornamenting machine, the combination with at least one ornamenting die, of a work support provided with a blind slot adapted to receive at least the front portion of a folded fitted shoe upper, at least a portion of the work support being interposed between the opposite side faces of the folded fitted upper, at least one side face of the folded fitted upper being interposed between the work support and the die. 10 15

27. In an ornamenting machine, the combination with at least one ornamenting die, of a work support provided with a blind slot adapted to receive at least the front portion of a folded fitted shoe upper, said slot having an edge adapted 20 to engage at least a portion of the inside median line of the folded fitted shoe upper.
